Office of the Clerk, South Middleton
Township, and State of Pennsylvania.

Letters Patent

The schedule referred to in this Letters Patent and making
part of the same, containing a description in the words of the
said John B. Green for himself of his improvement in
the machine for threshing and cleaning Clovers and

To all to whom these presents shall come,
Be it known that John B. Green for of South Middleton
Township, Cambria County and State of Pa have invented
a new and useful improvement in the machine for threshing
and cleaning Clovers and, and that the following is a full
and exact description and construction and operation of the
said machine as invented or improved by me.

The machine is designed to be propelled by one or more
horses, and to move them the power as usually
applied to the ordinary threshing machine here in use, the cog
wheel turns a shaft which by a band turns the cylinder of
the machine in the same manner that the cylinder of Humphreys
threshing machine. The cylinder may be varied in size from
six to twenty four inches in diameter and from two to four feet
in length, with a concave extending from where the cylinder
is fixed round to the lower part of the hopper, the cylinder
is covered with sheet iron tightly fastened and from ten to
twenty six upward rows of iron spikes or screws extending
out from one to two inches the concave is divided in
two parts, the two foot part commencing at the hopper
are covered with sheet iron and having eight to ten rows
of spike or screws similar to them in the cylinder, in the
two next parts is placed a wire screen than another two

two another stone with two rows of spikes 10 rows, then another stone
with two rows of spikes 10 rows, then another stone, which will
have one tenth part to receive the seed, at which place the hopper
is placed, the spikes 10 rows on the cylinder are placed regular
but alternately with those on the concave and play between them
in the rotation of the cylinder, which the concave is placed a
conductor to conduct the seed to the center immediately below
the cylinder where it falls on a iron sifters and is cleaned
by the fans placed under the conductor, the fans are similar
to those used in windmills, and turned by a band from a
small pulley on the cylinder shaft, so the hopper is placed
a roller with 12 or 15 rows of spikes 10 rows of which is turned
by a band from the shaft of the fan, which will pull the
machine, and between the first 10 rows and 10 rows in the con-
cave a space of one inch is left open to give it air, the
machine is firmly placed and turned on a frame similar
to Humphrey's Improved Threshing Machine, what is claimed
is new invented or discovered in the machine are the two
row spikes or rows, and the iron sifters or scones on the
concave and in the adaptation of the machine to the threshing
or cleaning of clover seed.

In testimony that the above is a full description
of my improvement as invented by me, I have hereunto
set my hand, this twentieth day of February in the
year eighteen hundred and thirty six.
